AUTOMATIC ASHTRAY FEEDER CONTAINER

Abraham Baff, North Arlington, N. J.

Application August 20, 1938, Serial No. 225,871

2 Claims. (Cl. 312—43)

My invention relates to improvements in dispensing apparatus or devices, particularly to an automatically acting feeder for articles, such as for instance trays or coasters, and more particularly ashtrays stacked in a container in any suitable size and number depending upon the size of the container.

It is one of the principal objects of my invention to provide such a device the tray container 10 of which can be made of any suitable material as for instance, glass, pottery, metal or the like and can have any color and shape to give it a pleasing and ornamental appearance. In this container a plurality of ashtrays of any suitable material are stacked so that as the top ashtray is removed, the other trays below the same are automatically raised to a point adjacent the upper or open end of the container for ready removal and the container will always present the 20 appearance of being filled.

Another object of my invention is the provision of such a device having its upper margin provided at certain points with suitably cut out places so that the fingers can easily grip the margin of the uppermost tray for its ready removal from the container.

Still another object of my invention is the provision of a device of this character in which the stacked ashtrays rest on a suitable support 30 as for instance a disc which is automatically and successively fed towards the open top of the container by means of a helical spring adapted to rest flat upon the bottom of the container and engaging said disc for their automatic feeding 35 towards the open top of the container.

A further object of my invention is the provision of a tray dispensing device the container of which is equipped at its upper margin with a plurality of cigarette or cigar rests which are 40 secured to the container and project over the inner margin at the upper end of the container so as to stop the feeding of the trays when the uppermost tray has been removed.

A still further object of my invention is the 45 provision of a container for the ashtrays which may be provided with a handle or handles and in which one or more cigarettes may be placed in any one of the trays or paper napkins or the like may be disposed between the individual trays.

50 These and other objects and advantages of my invention will become more fully known as the description thereof proceeds and will then be specifically defined in the appended claims.

In the accompanying drawing forming a material part of this disclosure:

Fig. 1 is a top plan view of an ashtray feeder constructed according to my invention.

Fig. 2 is a vertical section through the same on line 2—2 of Figure 1.

As illustrated, a container 10 of suitable shape 5 and material having a bottom 11 secured to its wall by means of the screws 12 has a spring 13 located therein which when compressed rests with its lower flattened portion upon said bottom, while its upper end bears against the underside 10 of the plate or disc 14 movably arranged within the container.

Upon this plate or disc rest a plurality of trays 15 nested so as to be individually and successively fed by the expansion of the spring towards 15 the open upper end of the container.

Cigarette or cigar rests are provided at the upper edge of the container and are designated 16, 17. They are fastened by means of screws 18, 19 to suitable shoulders in the container, and extend with their inner ends over the outer margin of the uppermost tray to hold the feed when this tray has been removed by the fingers gripping its margin through the depression 20 in the upper margin of the container. If desirable, a 25 cigarette 21 may be placed between two trays, while the trays may be lined with suitable paper napkins 22 or the like and the container may or may not be provided with suitable handles. 20

In use, the trays are stacked upon the spring 30 supported bottom disc movably arranged within the container and when pressed down, compressing the spring, the uppermost tray will engage with its outer margin the underside of the cigarette or cigar rests at the inner end thereof to 35 hold the spring compressed. When now one or more trays are removed by fingers gripping their margins through the depressions 20, the spring will gradually expand and feed the trays successively to the open end of the container. Handles 40 may be provided for suitably handling the device, and if so desired, cigarettes held between two adjoining trays may be successively presented to a smoker while the napkins between the individual trays will serve any desired purpose. 45

It will be understood that I have shown and described the preferred form of my invention as one example only of the many possible ways to practically construct the device, and that I 50 may make such changes in the general arrangement of the same and in the construction of its minor details as come within the scope of the appended claims without departure from the spirit of my invention and the principles involved. 55

Having thus described my invention, what I claim as new, and desire to secure by Letters Patent is:

1. A feeder for automatically feeding and delivering ashtrays comprising a container having a bottom and an upstanding wall, and an open top, a movable plate in said container, a helical spring having a flat bottom resting on the bottom of said container, and engaging said plate for gradually feeding the said plate towards the open top of the container, said container having a plurality of depressions in its upper margin to present a fingerhold for gripping the uppermost ashtray to facilitate its removal from the container, and a means to stop the feeding upon the removal of the individual uppermost ashtray of the stack.
2. A feeder for automatically feeding a stack

of ashtrays and delivering the same comprising a container having a bottom and an upstanding wall, said container being open at the top, a plate movably disposed in said container, a spring between the bottom of said container and said movable plate, a plurality of movable elements secured on the upper margin of said container and adapted to project into the path of the nested ashtrays fed during the expansion of said spring gradually and individually towards the open top, said elements constituting stops to stop the feeding of the ashtrays upon the removal of the individual uppermost ashtray, and said container having recesses in its upper margin to facilitate the gripping of the uppermost tray of the stack coming into alignment with the recesses.

ABRAHAM BAFF.
